FLUSH VALVE

Filed March 5, 1932

UNITED STATES PATENT OFFICE

1,931,608

FLUSH VALVE

Charles W. Hess, Middletown, N. Y.

Application March 5, 1932. Serial No. 597,029

7 Claims. (Cl. 137—93)

This invention relates to certain new and useful improvements in flush valves.

The primary object of the invention is to provide a flush valve especially designed for use in connection with water closets wherein the usual flush tank is eliminated and the control of the flow of water from a service pipe to the bowl of the water closet is accomplished by the interpositioning of the flush valve between the water service pipe and water closet bowl.

A further object of the invention is to provide a flush valve of the foregoing character wherein the valve embodies a casing having a partition therein between the water supply inlet to the casing and the valve controlled outlet from the casing to reduce pressure on the valve and eliminate hammering action thereof for the more effective operation of the valve.

A still further object of the invention is to provide a flush valve for water closets set into a water service pipe and operating in the absence of the usual flush tank with a float member connected to the valve within a casing and seating in a cup member having a restricted outlet to effect easy and slow closing movement of the valve on its seat.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a vertical longitudinal sectional view of the flush valve showing the casing, the water baffle and the valve mechanism;

Figure 2 is a horizontal sectional view taken on line 2—2 of Figure 1, showing the mounting guide for the water baffle or partition within the casing;

Figure 3 is a fragmentary side elevational view of the lower end of the casing with the operating handle and its associated parts for the valve mechanism removed; and

Figure 4 is a perspective view of the handle operated part or stem of the valve mechanism.

Referring more in detail to the accompanying drawing, there is illustrated a flush valve for water closets operating in the absence of the usual flush tank and controlling direct communication between a water service pipe and the bowl of the water closet, the flush valve comprising a casing 10 having the open exteriorly threaded upper end thereof closed by a screw cover 11, movement of which is facilitated by the integral polygonal nut projection 12 rising centrally from

the cover 11. The lower end of the casing 10 tapers inwardly as at 13 and carries an inwardly directed flange 14, the inner face of which is tapered to provide a valve seat and said casing below the tapered end 13 extends downwardly in cylindrical formation as shown at 15 providing a chamber 16 below the valve seat 14 for housing a part of the valve operating mechanism. The lower end of the cylindrical portion 15 of the casing is externally threaded as at 17 to facilitate attachment to an L or other part of the water closet for directing water into the water closet bowl.

A nipple 18 is carried by the upper end of the casing 10 for attachment to a water service pipe 70 and to reduce the rush of water through the opening in the valve seat 14, there is provided a baffle or partition within the casing between the water inlet nipple 18 and the valve seat 14. The partition or water baffle 19 is in the form of a plate shaped to have its edges contact the side walls of the casing 10 and its tapered lower end 13, the baffle plate 19 being retained in position by guide lugs 20 carried by the inner face of the casing 10 adjacent its upper end while 80 the lower end of the baffle plate 19 is curved as at 21 away from the valve seat and toward the side of the casing 10 carrying the inlet nipple 13 with the lower edge of the baffle plate 19 engaged with the rib 22 projecting upwardly 85 from the lower tapered end 13 of the casing 10. The lower curved end 21 of the baffle plate 19 is provided with an opening 23 that is of a diameter greater than the diameter of the water passage through the nipple 18 so that the flow 90 of water through the casing 10 will have the pressure reduced when passing through the valve opening 14 as compared with the velocity when flowing through the inlet nipple 18. The baffle plate 19 divides the casing 10 into two spaced 95 chambers 24 and 25 and a part of the valve mechanism is disposed within the chamber 25.

As shown in Figure 1, the side of the baffle plate 19 facing the chamber 25 carries a bowl or cup-shaped member 26 open at its upper side 100 and having a depending bearing 27 for a valve stem 28, the bearing 27 being further braced by the bracket arm 29 extending from the baffle plate 19 beneath the cup-shaped member 26. The valve disk 30 is detachably engaged with the lower end of the valve stem 28 and a ball float 31 is removably engaged with the upper end of the valve stem and when the valve disk 30 is engaged with its seat 14, the ball float 31 is seated in the cup-shaped member 26. For pur-

poses presently to appear, the lower side of the cup-shaped member 26 adjacent to and laterally of the stem bearing 27 is provided with a small opening 32, preferably one-sixteenth inch in diameter.

5 The operating means for the valve 30 is associated with the lower cylindrical end 15 of the valve casing 10, the cylindrical end 15 carrying a horizontal outwardly directed bearing boss 33 through which the rod 34 of a part of the 10 valve operating mechanism extends to enter the chamber 15 and packed in the bearing boss as at 35 to prevent water leakage. The outer end of the bearing boss 33 is provided with a V-shaped socket formed by tapering opposed walls 36 shown more clearly in Figure 3, the bearing boss having an axial opening 37 therein for the mounting of the rod 34. The outer end of the rod 34 carries an enlarged cylindrical head 38 having opposite sides thereof adjacent the rod 34 tapered as at 39 to be received in the V-shaped socket in the outer end of the bearing boss 33. A transverse threaded opening 40 is provided in the head 38 to receive the shank 41 of the 15 operating handle 42. A casing cap 43 is threaded onto the bearing boss 33 as shown in Figure 1, with the closed outer end thereof spaced from the head 38 and carrying an external cushion block 44 forming a rest for the seat cover of a water closet, a side wall of the casing cap 43 having an opening 45 therein for passage of the shank of the operating handle 42. A coil spring 46 is interposed between the outer closed end of the casing cap 43 and the outer end of the rod head 38 for normally seating the tapered sides 39 of the head 38 in the V-shaped socket in the bearing boss 33.

40 The inner end of the rod 34 that projects into the chamber 16 has one end of an angle arm 47 secured thereto as at 48, the other end of the angle arm 47 being loosely engaged as at 47a with the lower end of the valve operating rod 49 extending upwardly through a guide ring 50 carried centrally of a transverse spider arm 51 and terminating 45 adjacent the lower face of the valve disk 30.

45 In the operation of the flush valve, the handle 42 is shifted to impart rotary and axial movement of the rod 34 for moving the tapered end 39 of the head 38 out of the V-shaped socket in the outer 50 end of the bearing boss 33 against the tension of the spring 46, rotary movement of the rod 34 and angle arm 47 raising the valve operating rod 49 to unseat the disk valve 30 from its seat 14, the ball float 31 rising upwardly of its cup-shaped seat 55 with the water flowing through the valve opening and chamber 16 to enter the bowl of the water closet. The spring 46 immediately returns the head 38 and rod 34 to the position shown in Figure 1 with the valve operating rod 49 lowered out of the descending path of movement of the valve disk 30, the valve disk closing by its weight on the seal 14 and against the buoyancy of the ball float 31 lowering towards its seat and retarded in such movement by the ball float acting upon the water in the cup-shaped member 26, the water in the cup-shaped member slowing discharging through the opening 32 in the bottom thereof under confinement of the ball float. The valve disk 30 is normally retained on its seat by 60 water pressure in the casing 10, aided by the weight of the valve and stem carrying the same, the ball float 31 aiding in the unseating of the valve in the presence of an in-rush of water and flow through the valve casing while the closing 65 movement of the valve disk upon its seat 14 is 70 retarded as stated by the ball float 31 entering the cup-shaped member 26 and the slow discharge of water through the opening 32.

75 While there is herein shown and described the preferred embodiment of the invention, it is nevertheless to be understood that minor changes may be made therein without departing from the spirit and scope of the invention as claimed.

I claim:

1. A flush valve comprising a casing having a water inlet adjacent the upper end thereof, a valve seat in the casing, a valve cooperating with the seat, a ball float carried by the valve, a partition in the casing having an opening therein adjacent its lower end and separating the inlet from the valve, and means cooperating with the ball float for retarding closing movement of the valve on its seat, the means for retarding closing movement of the valve including a cup-shaped member in which the ball float is received and a support for the cup-shaped member carried by the partition above the opening therein.

2. A flush valve comprising a casing having a valve seat therein, a valve cooperating with the seat, a ball float carried by the valve, means cooperating with the float for retarding closing movement of the valve on its seat, the means for retarding closing movement of the valve including a cup-shaped member in which the ball float is received, said cup-shaped member being constructed to permit gradual escape of water therefrom during seating movement of the ball float, a water baffle partition in the casing at one side of the valve, the cup-shaped member supported on the partition, a stem connecting the valve and float, and a guide for the stem carried by the cup-shaped member.

3. A flush valve comprising a casing having a valve seat therein, a valve cooperating with the seat, a ball float carried by the valve, means cooperating with the float for retarding closing movement of the valve on its seat, manually operable means engageable with the under side of the valve for unseating the same, the means for retarding closing movement of the valve including a cup-shaped member in which the ball float is received, said cup-shaped member being constructed to permit gradual escape of water therefrom during seating movement of the ball float, a water baffle partition in the casing at one side of the valve, the cup-shaped member supported on the partition, a stem connecting the valve and float and a guide for the stem carried by the cup-shaped member.

4. A flush valve comprising a casing having a valve seat therein, a valve cooperating with the seat, a ball float carried by the valve, means cooperating with the float for retarding closing movement of the valve on its seat, the means for retarding closing movement of the valve including a cup-shaped member in which the ball float is received, said cup-shaped member having a small opening in its lower side for the exit of water during seating of the ball float in the cup-shaped member, a water baffle partition in the casing at one side of the valve, the cup-shaped member supported on the partition, a stem connecting the valve and float and a guide for the stem carried by the cup-shaped member.

5. A flush valve comprising a casing having a valve seat therein, a valve cooperating with the seat, a ball float carried by the valve, means cooperating with the float for retarding closing movement of the valve on its seat, manually operable means engageable with the under side

of the valve for unseating the same, the means for retarding closing movement of the valve including a cup-shaped member in which the ball float is received, said cup-shaped member having a small opening in its lower side for the exit of water during seating of the ball float in the cup-shaped member, a water baffle partition in the casing at one side of the valve, the cup-shaped member supported on the partition, a stem connecting the valve and float and a guide for the stem carried by the cup-shaped member.

6. A flush valve comprising a casing having a valve seat therein, a valve cooperating with the seat, a ball float carried by the valve, means cooperating with the float for retarding closing movement of the valve on its seat, manually operable means engageable with the under side of the valve for unseating the same, the valve operating means including a lifting rod for the valve separate therefrom to permit movement of the lifting rod independently of the valve, a bearing carried by the casing, a rod rotatably and axially shiftable in the bearing engageable with the valve lifting rod and means carried by the rotatable rod and means carried by the rotatable

rod and engaged with the valve lifting rod for normally holding the latter in inoperative position with respect to the valve.

7. A flush valve comprising a casing having a valve seat therein, a valve cooperating with the seat, a ball float carried by the valve, means cooperating with the float for retarding closing movement of the valve on its seat, manually operable means engageable with the under side of the valve for unseating the same, the means for retarding closing movement of the valve including a cup-shaped member in which the ball float is received, the valve operating means including a lifting rod for the valve separate therefrom to permit movement of the lifting rod independently of the valve, a bearing carried by the casing, a rod rotatably and axially shiftable in the bearing engageable with the valve lifting rod and means carried by the rotatable rod and engaged with the valve lifting rod for normally holding the latter in inoperative position with respect to the valve.
